CLAIM

The ornamental design for a wearable robot for fitness and walking assistance, as shown and described.

DESCRIPTION

FIG. 1 is a front perspective view of a wearable robot for fitness and walking assistance showing my new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is an enlarged view of the portion 9 encircled in FIG. 1;

FIG. 10 is an enlarged view of the portion 10 encircled in FIG. 1; and,

FIG. 11 is an enlarged view of the portion 11 encircled in FIG. 1.

The dashed broken lines in the figures depict portions of the wearable robot that form no part of the claimed design. The dot-dot-dash broken lines in the figures encircling portions of the claimed design that are illustrated in enlargements form no part of the claimed design.

1 Claim, 11 Drawing Sheets
